INVENTOR.

UNITED STATES PATENT OFFICE.

JOHN W. SHEPERDSON, OF WESTMONT BOROUGH, PENNSYLVANIA.

ROLLING-MILL APPARATUS.

1,100,404.

Specification of Letters Patent. Patented June 16, 1914.

Application filed November 13, 1912. Serial No. 781,077.

To all whom it may concern:

Be it known that I, JOHN W. SHEPERDSON, a subject of the King of Great Britain, residing in the borough of Westmont, in the 5 county of Cambria and State of Pennsylvania, have invented certain new and useful Improvements in Rolling-Mill Apparatus; and I do hereby declare the following to be a full, clear, and exact description of the 10 invention, such as will enable others skilled in the art to which it appertains to make and use the same.

My invention relates to rolling mill apparatus with special reference to the guide equipment thereof and is applicable to metal rolling mills known as two-high and three-high mills, and is particularly adapted to use in connection with those of the continuous type.

20 Although my invention is adapted for use in connection with blooming mills, billet mills, bar mills and rod mills, I will, for the sake of simplicity of description, refer to the rolled piece in all cases as a bar.

25 One of the objects of my invention is to provide a construction and arrangement of the delivery guides which receive and direct the rolled bar as it issues from one of the passes of the rolls.

30 A particular object of my invention is to provide delivery guides for rolls that have their available surfaces as fully utilized as practicable for adjoining roll passes, whereby each set of rolls is adapted to operate on 35 a number of bars, either separately, or on more than one at a time, and these adjoining passes may be of similar contour or of different contours, as desired.

In order that the rolling operation may 40 not be interrupted, I may provide in each set of rolls a plurality of passes of the same contour, whereby the rolling operation of any size and section may be shifted from one pass to another, in case where the first 45 pass becomes worn or otherwise inoperative for the purpose intended. I may also provide passes of different forms in the same pair of rolls adapted to operate upon and produce different sizes and sections, if desired.

50 My invention provides apparatus which has, by reason of its distinctive construction,

such a reduced lateral displacement that a simultaneous guide equipment is provided for adjoining roll passes, whereby the guide 55 of one pass will not interfere with the guide of the adjacent pass.

Another object of my invention is to standardize the roll guides, whereby I use the same equipment for various different 60 sizes and sections of bars. I have discovered that a guide to be efficient need not exactly conform to the shape or width of the guided bar, but can principally confine the top and bottom surfaces of the same, and I 65 have therefore dispensed with the customary adjustable side guide pieces and the interior lateral dimensions of my guides are limited only by the partitions or walls of the guide boxes which form part of my construction, 70 and which support the top and bottom guides.

By reason of my construction, bars of different widths, less than that between the partitions, may be guided without laterally 75 adjustable side guides, thereby increasing the range of the apparatus. I guide the rolled bar by a top and a bottom guide piece which contact therewith and are adapted for vertical adjustments as hereinafter de- 80 scribed.

By reason of the construction and vertical adjustment of my top and bottom guides, the movements of rolled bars of various shapes and of different thicknesses may be 85 efficiently regulated, and the lateral dimensions of said bars are limited only by the distance between the lateral walls of the guide box, while the vertical dimensions of the guided bar are only limited by the extreme 90 extent of the vertical adjustments of the top and bottom guide pieces.

By dispensing with the heretofore used adjustable side guides I also obviate the necessity of providing lateral retaining devices therefor, whereby I economize correspondingly in widths of construction, thereby minimizing the amount of separation of the two adjoining guides to the thickness of the partitions serving as the side walls of the 95 100 guides.

My guide construction is adapted for flat bars which are not axially turned or twisted when passing from one set of rolls to the

other and is also adapted to be used as a twist guide which axially turns or twists a bar as it is delivered from one set of rolls to cause it to enter the pass in the next set 5 of rolls in a different position. The vertical adjustments applied to my twist guides are adapted to determine and regulate the extent of the twist, thus standardizing the twist guides and rendering them applicable 10 to various conditions which heretofore required a multiplicity of twist guides, each of a distinct formation and pitch of twist.

In order to more fully describe my invention, I will now refer to the accompanying 15 three sheets of drawings on which like numbers indicate like parts.

Figure 1 is a transverse sectional elevation through a pair of two-high rolls, showing the rolls in section, the housing in elevation 20 and my guides in longitudinal sectional elevation. Fig. 2 is a front elevation on an enlarged scale of my delivery guides with two rolled bars shown in cross section passing there-through. Fig. 3 is a top plan view 25 of my delivery guides with the parts thereof assembled in position. Fig. 4 is a transverse section through a pair of rolls showing the bottom of my delivery guide-box and the guide rest in section and a pair of twist 30 guides and other parts in side elevation. Fig. 5 is a top plan view of an entering guide adapted to coöperate with the rolls and the delivery guides. Fig. 6 is a vertical longitudinal elevation of the entering guide 35 taken on the line VI—VI of Fig. 5. Fig. 7 is a front elevation of a form of my delivery guide in which the guide-boxes are separate for each pass, as shown, thereby permitting 40 replacement and adjustment of one guide without interfering with the others. Fig. 8 is a perspective view of a liner which may be inserted between the bottom guide piece and the bottom of the guide box to adjust 45 the elevation of the bottom guide pieces as desired. Fig. 9 is a perspective view of a shim 24 which may be inserted to adjust the top guide nearer to, or farther from, the rolls, as desired. These shims may be of 50 different thickness to accomplish this purpose.

Referring now to the characters of reference on the drawings:—1 is the top roll of a two-high mill, 2 is the bottom roll of the same and as viewed in Fig. 1, these rolls are 55 adapted to rotate in such directions that the contiguous portions of their peripheries move from left to right, the movement of the bar in the pass being in a similar direction.

60 3 is a part of a bar or billet on the entering side of the rolls; 4 is that part of the same between or within the bite of the rolls, and 5 is that part of the bar after it issues from the rolls in its reduced or shaped 65 form.

6 represents the bottom of the frame-work or box-like structures forming part of a support for my delivery guides; 7 are intermediate vertical partitions or walls thereof, while 8 are the corresponding end walls. 70 The intermediate walls or partitions 7 may be made integral as shown in Figs. 2 and 3, or they may be made separate from each other, as shown in Fig. 7. The arrangement of these partitions or walls, as shown in 75 Figs. 2 and 3, is a compact and solid construction, while the arrangement of the individual box-like structures shown in Fig. 7 is very similar, with the exception that the change in adjustment of each guide box 80 may be made without interfering with its companion. These guide boxes are of channel shape in cross section, that is, closed on the bottoms and sides, and open at the ends and top, the said top, however, being closed 85 by the top guide and the bottom provided with a separate bottom guide when the various parts are assembled for operation. The guide boxes are mounted upon the guide rest 9 or are supported on brackets, or otherwise, on the roll housings.

10 are holding down bolts which secure the delivery guide to the guide rest 9, passing through the slotted holes in the latter, which holes are longer and wider than the 95 diameter of the bolts 10, as shown, to admit of slight longitudinal or lateral adjustment, as may be required.

11 are the bottom guide pieces mounted within the guide boxes between the partitions thereof and resting on the bottom 6 as shown. Between the bottom guides 11 and the bottom 6, shims, such as 45, illustrated in Fig. 8, may be inserted, these being of varying thicknesses or number, whereby the 100 vertical adjustment of the said bottom guides is accomplished. These shims are preferably formed with an elongated opening extending from one end thereof, so that they are adapted to be slipped into place 105 under the bottom guide without interfering with the bolt 10 or the lug 13. The forward or tongue ends of the bottom guide pieces 11 are indicated as 12 and these are curved and pointed, as shown, and adapted to rest in 110 contact with or near the surface of the pass in the bottom roll. The bottom guides 11 are each provided with lugs 13 which project from the lower surface thereof adapted to contact with the wall of the opening 14, 115 provided for this purpose in the floor 6 of the guide boxes. In order to allow a longitudinal adjustment of the bottom guide, shims or liners, indicated as 15, may be inserted between the flat end of the lug 13 120 and the wall of the hole 14, thereby holding the guide firmly in position against the thrust of the moving bar contacting with its upper surface.

16 represents upper guide pieces which are 130

fitted between the partitions formed by the walls 7 and 8 as shown. These upper guides are provided with projecting lugs 17 adapted to overlap the upper surface of the said walls 7 or 8. These lugs are preferably arranged in staggered relation with each other, as shown in Fig. 3, which makes a compact arrangement and reduces the width of the construction for the purposes desired. The lugs 17 of the upper guide 16 are provided with set screws or tap bolts 18 mounted within threaded holes provided therefor, whereby the guide 16 may be raised or lowered on either or both sides and ends as desired. Standards 19 are preferably formed integral with the walls 7 and 8 and project upwardly therefrom, these standards being formed in pairs with an opening between, in which a clamp bar 20 is inserted and secured by the pin 21 which passes through the slotted holes provided therefor in said standards, thereby securing said clamp bar in position as required and allowing the same to be removed when desired. The lower edge of the clamp bar 20 is preferably curved in cross section, as shown, to accommodate the wedge surfaces in contact therewith. The tapered key or wedge 22 is adapted to be inserted and driven between the clamp bar 20 and the upper surface of the guide piece 16 for the purpose of securing said guide firmly in position and well adapted to resist the upward thrust or twist communicated to it by the roller bar, these forces being very considerable in amount, especially when guiding bars or large sections. Lugs 23 are formed on the intermediate portion of the upper surface of the top guides 16 adapted to cooperate with the side of the clamp bar 20 to hold said guides in position longitudinally to resist the thrust of the guided bar. In order to obtain forward or backward adjustment of the top guide 16, shims such as 24 may be inserted between the lug 23 and the side of the clamp bar 20, whereby said top guide is held in position, nearer to, or farther from the rolls, as desired. More or less of these shims may be used of varying thickness, to accomplish the purpose desired. The shim 24 is preferably formed of a rectangular piece of flat steel provided with a central opening, as shown, through which opening the clamping wedge 22 is adapted to pass without disturbing the shim, while the lower edges of said shim rest on the upper surface of the top guide 16.

As shown in the intermediate portions of Fig. 2 and in Fig. 4 the lower guide 11 and the upper guide 16 are formed with their interior surfaces transversely inclined throughout the major portions of their lengths. Adjoining the roll pass these surfaces are parallel with the cylindrical surfaces of the grooves in the roll, but as they depart from said grooves, they are formed

with a slow pitch after the fashion of an auger or a twisting device. These twist guides are adapted to twist the bar axially, so as to present it to the next pass of the rolls in a different position, whereby the work and reduction on said bar will be in a different direction. In order to more readily accomplish the purpose intended and to make these twist guides of universal adaptation they are provided with portions 25 projecting from the surfaces thereof, which projections are so located as to contact with those portions of the sides of the bar diagonally opposite each other, whereby the twisting is more readily accomplished and adjusted, as the guiding surfaces contact with the parts of the bar best adapted to cooperate in producing the twist desired.

The inner edges of the ends of my guides are adapted and arranged to be near, or in contact with, the surfaces of the roll passes which they serve, so as to neatly guide the delivered bar by contact with portions of the surfaces thereof as required, and all the adjustments of said guides are made in such a manner as to maintain this proper relation between the guides and the roll passes.

When it is necessary to adjust the guides to modify the delivery direction of any particular bar, after the guides have once been set for that pass, the greater part of the vertical adjustments of my guides is made at the ends thereof which are farthest from the roll passes, and the shims, set screws, wedges, etc., are arranged accordingly. The shims near the outer ends may be thicker or greater in number than those near the inner ends of the guides, and the set screws may be moved through a greater range to accomplish this particular adjustment.

The housing of the rolls is indicated as 26, the housing cap is indicated as 27, while 28 represents an entering guide which is supported at one end on the guide rest mounted on the housings as shown, while the other end 46 of said entrance guide is supported on the pedestal 29, which latter is provided with a suitable base secured to a solid foundation (not shown). The entering guide is provided with side guides 30 formed integral therewith and preferably tapering from their inner ends to their outer ends, as shown, thereby providing guiding passages to the roll passes. The outer part 46 of the base of the entering guide is sloping as shown, thereby forming an inclined surface to better receive and direct a bar to the roll pass in connection with the tapering side guides 30, 34, 35 and the sloping cover 37, thus forming an adjustable funnel-shaped construction adapted to guide bars of different sizes and forms. The entering guide plate is secured in position by the bolts 31 which pass through slotted holes 32 provided therein and is locked in

position by the keys 33 which pass through slots in the ends of the bolts 31 as shown. Only one of each pair of bolts 31 may be used and its head may be seated in either of the 5 slots in the pedestal 29, or in either of the slotted holes 32 in each of the entering side guides 30, thereby providing different positions of the entering guide, as desired. Further smaller adjustments of the same 10 can be made by reason of the slotted holes 32 provided for this purpose. This arrangement permits lateral and longitudinal adjustment of the entering guides to adapt them to coöperate with the rolls as desired. 15 The inner ends of the entering side guides 30 are provided with intermediate swinging side guides 34 and the outer swinging side guides 35. These swinging guides adjoin the rolls and are adapted to be moved laterally and secured in position to accommodate 20 and guide bars of different widths. These adjustable side guides 34 and 35 are hinged and pivoted to the fixed side guides 30 by the pivot pins 36 as shown, which 25 pass through the hinge lugs 40, 41 and 42 formed thereon, as shown clearly in Figs. 5 and 6. The inner end of the entrance guide is supported on a guide rest by means of its projecting lugs 43 which contact there- 30 with, as shown in Fig. 1. The upper edges of the inner ends of the adjustable entrance guides 34 and 35 are elevated and tapering as shown and each pair is provided with a cover 37, which rests on the aforesaid upper 35 edges of the adjustable swinging guides to hold them firmly in the position desired, thereby forming a closure and completing the tapered guide opening. Short bars or blocks 38 rest on top of the tapered ribs 40 or flanges of each of the covers 37 and hold them and the swinging guides firmly in place by the action of the keys or wedges 39 which are driven between the bars 38 and the longer bar 44, which latter is se- 45 cured at each end to the roll housing, thereby serving as an abutment against which the wedges 39 operate.

My delivery guide for flat bars can be adjusted for different thicknesses of bars 50 by raising or lowering the bottom guide piece 11 by introducing or withdrawing shims between the bottom thereof and the upper surface of the guide-box 6 and adjusting the bolt 10, while the backward and 55 forward adjustment of the guide piece may be made by introducing or withdrawing shims 15. The vertical adjustment of the top guide for flat bars may be made by screwing or unscrewing the tap bolts 18 60 and then driving the wedge 22 to firmly secure said top guide in position.

My twist guides may be adjusted for different thicknesses of bars in manner

similar to that just described in connection with the guide for flat bars.

In addition to the adjustments of my guides to accommodate bars of different thicknesses, my twist guides can be adjusted to produce more or less twist in any given bar by moving the outer ends of said twist guides nearer together, or farther apart, respectively. When the outer ends of the twist guides are moved closer together this will produce more twist due to the action on the bar of the guiding surfaces and the diagonally arranged projections 25 thereon, while less twist will be produced when the guides are adjusted a farther distance apart. This, therefore, provides a ready and convenient means for regulating the amount of twist produced in a bar between one roll pass and the next pass, whereby the bar is properly delivered for entry and reduction in the required direction.

It will be understood that the pitch or 8 amount of the twist in any given axial length of the twist guides may be such that the continuation of said twist by the movement of the bar, in contact with said guides, will bring it into proper axial position for 9 the next pass; for example; if a rectangular bar requires to be given a one-quarter turn, that is, rotate 90 degrees between one roll pass and the next, the length of the guide being 20-inches, and the distance between 95 the roll passes 8-feet, 4-inches, or 100 inches, the twist guides in such case should be so adjusted as to turn the bar axially through one-fifth of the total amount, viz.:—18 degrees, and the continued movement of said 10 bar through the remaining distance to the next pass will bring it into the desired position. Heretofore these adjustments had to be made in the first formation and construction of the twist guides, leaving no latitude for adjustment, whereas, by means of my arrangement this can be done in a very simple way, irrespective of the wear of the guides, variations in heat or stiffness of the bar, or other complicating causes.

From the foregoing it will be obvious to those skilled in this art, that my guide equipment, comprising boxes and adjustable guides mounted therein, provides such a compact and at the same time universal and 115 adjustable construction that all the roll passes are equipped with guides at the same time, even when the available roll surface is as fully utilized as possible for grooves therein.

Although I have shown and described my improvements in considerable detail, I do not wish to be limited to the exact and specific details shown and described, but may use such substitutions, modifications or 125 equivalents thereof, as are embraced within

the scope of my invention, or as pointed out in the claims.

Having thus described my invention, what I claim and desire to secure by Letters Patent is:—

1. A rolling mill delivery guide comprising a guide-box of open channel section, a bottom guide mounted therein, a top guide mounted in and between the upper portions of said guide-box and provided with projections extending over the upper edges of the same, and means for adjusting and securing said guides in position.

2. A rolling mill delivery guide comprising a guide-box with open top and ends, a bottom guide mounted therein, a top guide mounted in and between the upper portions of said box and provided with projections extending over the upper edges of the same, set screws mounted in said projections adapted to contact with the said upper edges, and means for securing said guides in position.

3. A rolling mill delivery guide comprising a guide-box of channel section with open top and ends, a bottom guide mounted on the lower inner surface thereof and provided with means for vertical and longitudinal adjustment therein, a top guide mounted in and between the upper portions of said box and provided with projections extending over the upper edges of the same, set screws mounted in said projections adapted to contact with the said upper edges, a clamp bar secured to and above said box, and clamping means between said clamp bar and the upper surface of said top guide, whereby the same may be adjusted and firmly secured in position.

4. A rolling mill delivery guide comprising a guide-box of open channel section provided with a pair of bifurcated standards extending above the side walls thereof, a bottom guide adjustably mounted in said box, a top guide mounted in and between the upper portions of said box and provided with projections extending over the upper edges of the same, set screws mounted in said projections and adapted to contact with the said upper edges, a clamp bar mounted and secured within the bifurcations of the standards, and clamping means between said clamp bar and said top guide, whereby the same may be adjusted and firmly secured in position.

5. A rolling mill delivery guide comprising a guide-box of open channel section, a pair of bifurcated standards formed integral therewith and extending above the side walls thereof, a top guide mounted between the upper portions of said box and provided with projections extending over the upper edges of the same, set screws mounted in

said projections and adapted to contact with said upper edges, a clamp bar removably secured within the bifurcations of the standards aforesaid, and a wedge between said clamp bar and said top guide; whereby the same may be adjusted in position by means of the set screws and firmly secured in position by said wedge.

6. A rolling mill delivery guide comprising a plurality of guide-boxes of open channel section, the side walls of which are contiguous, bottom guides and top guides mounted in said boxes and provided with means for adjusting and securing said guides in position, thereby forming a plurality of adjustable openings in alignment with the corresponding roll passes.

7. A rolling mill guide comprising a guide-box of open channel section, a bottom guide mounted therein and provided with an inner laterally sloping twisted surface, a top guide mounted between the upper portions of said guide-box and similarly provided with an opposing inner laterally inclined twisted surface, thereby forming a twisting opening, and means for adjusting and securing said guides in desired positions.

8. A rolling mill guide comprising a guide-box of open channel section, a bottom and a top guide mounted therein, each provided with a laterally sloping twisted inner surface, thereby forming a twisting opening extending from the roll pass, means for vertically adjusting said guides as desired, and clamping means adapted to secure the same in position.

9. A rolling mill guide comprising a guide-box of open channel section, a bottom and a top guide adjustably mounted therein, said guides being provided with laterally sloping opposed twisted surfaces and longitudinally extending projections on the diagonally opposite portions of said surfaces.

10. A rolling mill guide comprising a plurality of boxes of channel section open at their tops and ends, the sides of the same being contiguous, the longitudinal openings thereof being respectively opposite a series of roll passes, a bottom guide and a top guide mounted in each of said boxes, and means for adjusting and securing said guides in desired positions.

11. A rolling mill guide comprising a plurality of laterally contiguous boxes open at their tops and ends, the intermediate dividing walls of which are common to the adjacent boxes, a bottom guide mounted in each of said boxes and provided with means for adjusting and securing the same therein, a top guide mounted between the upper portions of each of said boxes and provided with projections extending over the upper edges of the same, adjusting means coöoperating

with said projections and upper edges, and means for clamping said guides to said boxes in predetermined positions.

12. A rolling mill guide comprising a flat base portion and a plurality of dividing walls extending above the same thereby forming a series of open channels, a bottom guide mounted in the lower portion of each of said channels and provided with means for adjusting and securing the same therein, a top guide mounted in the upper portions of each channel and provided with lugs extending over the upper edges of the adjacent

walls, the lugs on adjoining top guides being located in staggered relation with each other, set screws mounted in said projections adapted to adjust said top guides, and clamping means adapted to firmly secure said top guides in their adjusted positions. 15

In testimony whereof I hereto affix my 20 signature in the presence of two witnesses.

JOHN W. SHEPERDSON.
